UNITED STATES PATENT OFFICE.

ALBERT C. FISCHER, OF CHICAGO, ILLINOIS.

ROOFING ATTACHMENT.

Original application filed June 3, 1920, Serial No. 386,260. Divided and this application filed April 8, 1926. Serial No. 100,554.

This invention is a division of my application Serial No. 386,260, filed June 3, 1920, for roofing attachments, and relates particularly to means for securing the edges of overlapping areas of flexible roofing material, and has for its object to provide a cheap efficient and readily applied attaching means of sheet metal, which may be applied to the sheet roofing at the time of applying the roofing to a building, or at the time of preparing the roofing for application to a building, and which in one form will be self-attaching to the structure to which the roofing material is to be applied.

The invention proceeds upon the principle of forming a piece of sheet metal, including a base, with anchoring means presented from the underside of the base, attaching the device to serve as a roofing cleat, and having its anchoring means as well as the openings in the roofing material formed thereby, completely housed and protected from the weather. The anchoring means in one form being, as above stated, presented in position to be driven into the surface of the structure which is to receive the roofing material; or, as in another, thru an overlapped roofing sheet to serve as a means for uniting the sheets, and wholly separate from the feature of anchoring the roof to the building structure.

Two different embodiments of the invention are shown in the accompanying drawing by way of illustration. In said drawing Figure 1 is a perspective view of one form of cleat; Figure 2 is a view in side elevation, illustrating application of the form shown in Figure 1; Figure 3 is a perspective view of a modified form of cleat; Figure 4 is a perspective view of still another modified form; Figure 5 is a view in horizontal section illustrating the application of the form shown in either Figures 3 or 4; Figure 6 is a perspective view illustrating the application of that form of cleat shown in Figures 3 to 5 inclusive.

Referring now to the drawing in detail, —1— represents the base of the cleat, which according to Figures 1 and 2 comprises a relatively flat top portion, with relatively short weathering aprons 2 and 3 formed on the sides thereof, the apron —2— is simply a downwardly turned or deflected portion of the top —1—, whereas the apron —2— is a deflected portion of the top —1— which is

turned downwardly and then bent upon itself, with the underlying part —4— lying flush against the underside of the top —1— and terminating in anchoring means, comprising spurs or the like —5—. These spurs 60 are formed by stamping, or otherwise cutting the edge of the undeturned apron, to leave downwardly presented impaling points, as shown in Figure 2, with A and B representing the overlapping roofing material, the cleat is mounted upon the sheet A and with the spur —5— driven into the sheet A and into the sheet B, thus locking the two sheets together. The aprons 2 and 3 will bite into the material of the sheet A 70 to form a watertight joint, so as to completely cover the spur —5— and the opening which it makes in the sheets A and B.

In Figure 3 the base 1^a is made with a short apron 2^a with the opposite end of the 75 base turned under, as at 3^a and terminating with spurs 5^a. In this form the apron —3— is omitted.

The form shown in Figure 4 is identically the same as Figure 3, excepting that the 80 apron 2^b is somewhat longer than the apron 2^a. This, of course, is not a material difference and is only arranged in order to provide for different thicknesses of the sheets A and B. In any event, for either the form 85 shown in Figure 3 or Figure 4 the spur —5— will penetrate not only sheet A of the roofing material, as in Figure 2, but also passing completely thru sheet B and into the building structure to which the roofing is 90 to be applied. Instead of being raised above sheet A, as indicated in the form shown in Figure 2, the base 1^a lies flush with the surface of the sheet A, excepting for the double thickness 3^a made by turning the end of the 95 base under, which, of course, leaves a space between the surface of the sheet A and the underside of the base in front of the spur 5^a, which space is equal to the thickness of the undeturned portion 3^a. The cleat is 100 presented near the edge of the sheet A so that the apron 2^a overlaps the end of the sheet and protects the space between the sheets against the weather. In other words, although the overlap is made in the direction of the watershed, should wind blow the water back over the roof, as it often does, the weathering apron 2^b thoroughly protects the overlap in this respect. This also applies 105 to the relatively narrow weathering apron 110

2^a. The anchoring spur 5^a is completely protected by the base of the cleat, as well as the opening which it makes in the sheets A and B, so that the connection is practically 5 waterproof.

In producing these cleats I can turn them out in a very simple and inexpensive manner, for instance by stamping. They are exceedingly convenient to apply and serve 10 their intended purpose in a most efficient manner.

I claim:

1. In a roofing attachment, a sheet metal base having a portion thereof folded upon 15 itself to provide an underlap, an anchoring spur projecting from said underlap and protected by the overlying portions of the base.

2. In a roofing attachment, a sheet metal base having a portion thereof folded upon 20 itself to provide an underlap, an anchoring spur projecting from said underlap and protected by the overlying portions of the base, the folded portion of the attachment being

deflected from the plane of the base to provide a weathering apron. 25

3. In a roofing attachment, a sheet metal base having a portion thereof folded upon itself to provide an underlap, an anchoring spur projecting from said underlap and protected by the overlying portions of the base, 30 the folded portion of the attachment being deflected from the plane of the base to provide a weathering apron, said base also having its edge opposite the fold deflected to form a second weathering apron. 35

4. In a roofing attachment, a sheet metal base having a portion thereof folded upon itself to provide an underlap, and a nailing spur projecting from said underlap, and protected by the overlying portion of the base, 40 said base having its edge opposite the fold deflected to form a weathering apron.

Signed at Chicago, Illinois, this 30th day of March, 1926.

ALBERT C. FISCHER.
